(57) **CLAIM**

The ornamental design for a portion of a shoe midsole, as shown and described.

DESCRIPTION

FIG. 1 is a perspective view of a portion of a shoe midsole showing my new design;

FIG. 2 is a side view thereof; and,

FIG. 3 is a second perspective view thereof.

The uneven broken line immediately adjacent to the shaded area of the rearmost column-shaped feature represents an unclaimed boundary of the design. The uneven broken line showing of the remainder of the shoe is for illustrative purposes only and forms no part of the claimed design.
